UNITED STATES PATENT OFFICE

166,833

AUTOMOBILE

Houston Thompson, Milwaukee, Wis.

Application March 2, 1951, Serial No. 14,357

Term of patent 3½ years

(Cl. D14—3)

To all whom it may concern:

Be it known that I, Houston Thompson, a citizen of the United States, residing at Milwaukee, in the county of Milwaukee and State of Wisconsin, have invented a new, original, and ornamental Design for an Automobile, of which the following is a specification, reference being had to the accompanying drawing, forming part thereof.

Figure 1 is a side elevational view of an automobile showing my new design;

Figure 2 is a front elevational view thereof;

Figure 3 is a top plan view; and

Figure 4 is a rear elevational view of the same.

The essential features of my design are shown in full lines.

I claim:

The ornamental design for an automobile, as shown and described.

HOUSTON THOMPSON.
